UNITED STATES PATENT OFFICE.

MOSES STUART LEVUSSOVE, OF NEW YORK, N. Y.

TALKING-MACHINE.

1,279,375.

Specification of Letters Patent. Patented Sept. 17, 1918.

Application filed August 4, 1915. Serial No. 43,532.

To all whom it may concern:

Be it known that I, MOSES STUART LEVUSSOVE, a citizen of the United States of America, residing at New York city, in the county 5 and State of New York, have invented certain new and useful Improvements in Talking-Machines, of which the following is a specification.

My invention relates to phonographs and 10 more particularly to improvements in a type thereof wherein the sound box is propelled across a record in accordance with the groove of the record within which are the impressed sound waves.

15 There are in extensive use at the present time, phonographs of different types having in common the essential characteristic of a sound box propelled across a record in accordance with the record groove, said

20 sound box opening into a horn, amplifier or tone arm having movement with the sound box. In machines of the types above referred to, the sound box is commonly connected to the amplifier, horn or tone arm 25 through a metallic pipe section having a swiveling relation to said amplifier, horn or tone arm. It is also a common practice to transmit to this amplifier sound waves developed upon only one side of the dia-

30 phragm. In the types of machine above referred to, the tone arm ordinarily, has a swiveling action so as to cause the sound box, and stylus carried thereby, to describe an arc in its travel across the record. This 35 varies the relation of the stylus and succeeding spiral portions of the groove, which condition tends toward, not only a loss of accuracy in the reproduction, but rapid wear of the record.

40 In a machine made in accordance with my invention, the sound box has movement in accordance with the groove of the record having the impressed sound waves therein, said sound box, however, having a rectilineal

45 movement so that the stylus carried thereby will bear the same relation to every portion of the spiral groove, thus insuring greater accuracy in the reproduction and avoiding undue wear of the record. The sound box 50 is so supported with relation to the amplifier, horn or tone arm as to permit this move-

ment thereof across the record independently of said amplifier, horn or tone arm which, while the machine is in operation, has no movement across the record with the 55 sound box. The amplifier, horn or tone arm structure is preferably such as to compensate for variance in the plane of rotation of the record support, or the record thereon. The sound waves are transmitted from the 60 sound box to the amplifier, horn or tone arm through a supplemental tone arm leading from the sound outlet opening of the sound box, said supplemental tone arm having movement with the sound box. To insure 65 the free movement of the sound box across the record, I mount said supplemental tone arm in anti-friction bearings, and when sound waves are taken from both sides of the diaphragm mount both supplemental 70 tone arms in bearings accurately alined one with the other.

75 Preferably I so construct a phonograph made in accordance with my invention that the sound waves developed on both sides of the diaphragm will be transmitted to the amplifier, horn or tone arm, a construction which not only involves the duplication of the tone arm structure but the modification of the sound box in a manner to insure an 80 air chamber of substantially the same capacity upon each side of the diaphragm. The amplifier, horn or tone arm, the supplemental tone arm and the sound box are so constructed and related as to prevent the 85 application of excessive weight to the record through the stylus.

90 When taking sound waves from both sides of the diaphragm, the sound box and stylus arm are so arranged as to present no such 90 openings in the supplemental tone arm as will tend to permit the sound waves to pass therethrough before entering the amplifier, horn or tone arm. I also provide a stylus mount which will insure rigidity in the connection of the stylus with the pivotal stylus arm.

95 The invention consists in the novel features of construction and combination of parts hereinafter set forth and described 100 and more particularly pointed out in the claims hereto appended.

Referring to the drawings:—

Figure 1 is a plan view of a phonograph embodying my invention;

Fig. 2 is a side elevation thereof;

Fig. 3 is a section on the line 3—3 of Fig. 1;

Fig. 4 is a perspective view of a portion of one of the tone arms, one of the supplemental tone arms and the bearings for said supplemental tone arm carried by said main tone arm;

Fig. 5 is a vertical section of the sound box structure;

Fig. 6 is a side view thereof seen from the left of Fig. 5;

Fig. 7 is a side elevation of the sound box; and

Fig. 8 is a detail view of the support for restricting the stress upon the record from the reproducing mechanism.

Like letters refer to like parts throughout the several views.

In the embodiment of my invention shown in the accompanying drawings, *a* indicates 25 a cabinet having mounted thereon a rotatable record table *b* which may be driven in any desired manner. A record *c* of the usual gramophone type is shown on said table.

Mounted above said table in a manner to 30 have rectilinear movement across the record is a sound box *d* of the gramophone type. This sound box is so supported as to be propelled across the record *c* in accordance with the record groove. The said sound box is 35 provided with the usual vibratory arm *d'* carrying the stylus or needle point *d''*, and connected with the diaphragm *d'''* in a manner to impart vibrations thereto.

Carried by the cabinet *a* is an amplifier, 40 horn or tone arm consisting of a bell *e* preferably concealed within said cabinet, and a tapered arm having substantially parallel sections *e'*—*e''* and a connecting section *e'''*. The axis of the section *e'* is perpendicular to the plane of, and in axial alinement with, the diaphragm *d'''* and the section *e''* is pivotally mounted with relation to the bell *e* in a manner to permit the raising or lowering of the sound box for mounting a record 50 upon the table *b* or bringing the stylus *d''* into engagement with the record.

The sound box *d* is provided with a sound outlet *f* in communication with the section *e'* through a supplemental tone arm *f'* slidably mounted in a bearing *f''* carried by the 55 said section *e'*. To prevent a rotative movement of the sound box *d* and the arm *f'* with relation to the bearing *f''* or a resultant variance in the effective angular relation of 60 the stylus and the record, I provide means whereby the arm *f'* is restricted to a movement axially thereof. This means preferably comprises one or more guide ways *f'''* in said arm, and co-operating means, as the balls 65 *f''''* seated in fixed ball cups *f'''* carried by the

bearing *f''* and entering said guide ways *f'''*. This construction also affords an efficient anti-friction bearing for the arm *f'*. To give the necessary range of movement to the sound box *d* in traveling across the record, 70 the arm *f'* is elongated, as shown; the section *e'* being of sufficient length to permit the necessary telescopic action of the said arm *f'* in the said section *e'*.

The tone arm *f'* opens into the section *e'* 75 so as to transmit all sound waves thereinto.

To avoid binding of the supplemental or slidable tone arm *f'* in the bearing *f''*, I provide the side of the sound box opposite to that from which the arm *f''* extends, with 80 an elongated support *g'* slidably mounted in a bearing *g''* the axis of which is alined with that of the bearing *f''*. Rigidly attached to each of the bearings *f''*—*g''* is a connecting bar *h* for preserving the alinement of said 85 bearings. This bar is offset with relation to said bearings to afford a clear field for the sound box *d* when traversing the record.

The support *g'* preferably comprises a second supplemental tone arm, similar in all respects to the arm *f'*, the opposite ends thereof communicating with a sound outlet opening *g* on the side of the diaphragm opposite to the sound outlet opening *f* and with the section *i'* of an amplifier, horn or 95 tone arm, similar to the section *e'*.

The section *i'* is in axial alinement with the section *e'* and supports the bearing *g''* in the same manner as the said section *e'* supports the bearing *f''*. 100

By means of the supplemental tone arm *g*, sound waves are transmitted to a second amplifier, horn or tone arm consisting of a bell *i* opening adjacent the bell *e*, and a tapered arm having a section *i''* parallel with 105 the section *i'* and in communication therewith through the section *i'''*. The section *i''* is pivotally mounted with relation to the bell *i* upon an axis co-incident with the axis of the pivotal connection between the section 110 *i'''* and the bell *e*. I provide the bell *e*—*i* with a mouth section *j* common to both said bells and opening outwardly of the cabinet *a*. By this construction I am enabled to provide an amplifier, horn or tone arm mechanism having a single outlet opening and two branches communicating respectively with sound outlet openings on opposite sides of the diaphragm of a sound box. 115

In raising or lowering the stylus from the 120 record, both sections *e'*—*i'* have simultaneous similar movement, and the entire amplifier mechanism operates under identical conditions so as to constitute in its entirety a single reproducing mechanism. If desired, 125 one of the amplifiers, horns or tone arms may be dispensed with, without departing from the spirit and scope of the invention, although I prefer to use two tone arms as shown and described, as I have found that 130

this construction results not only in greater amplitude, but better timbre, in the reproduction.

To secure the results above referred to, I have found it necessary to so construct the sound box as to form an air column of equal volume on opposite sides of the diaphragm d^3 . This I do by inclosing both sides of the sound box by the parallel walls $k-l$, provided respectively with the sound outlet openings $f-g$ and the nipples $k'-l'$ leading therefrom and opening into the supplemental tone arms $f'-g'$ respectively.

The diaphragm d^3 is spaced away from the wall k the requisite distance with its edge suitably supported. Parallel with the diaphragm d^3 and spaced therefrom substantially the same distance, as the diaphragm d^3 is spaced from the wall k , is an annulus m , the opening m' of which is of substantially the same size as, and alined with, the sound outlet opening g . The arm d' projects through said opening m' .

The annulus m is spaced sufficiently away from the wall l to afford clearance for the free vibration of the arm d' , the outer edge of the sound box having an opening n therein, through which the said arm d passes. The opening n is so located with relation to the opening m' and the latter opening is so located with relation to the sound outlet opening g , that there is little or no tendency of the sound waves to pass through said opening n . By this construction, I also avoid any openings in the amplifier, horn or tone arm intermediate the diaphragm and the sound outlet g .

The edge of the annulus is suitably packed and insulated with relation to the sound box.

To insure the desired rigidity of the stylus or needle point d^2 with relation to the arm d' , I provide said arm with a mount consisting of an enlarged hollow head o having a split end forming jaws o' , the exterior of which is tapered and screw threaded, as shown; and a rotatable sleeve o^2 having screw threads coöperating with those on the head o . By this construction, the jaws may be closed firmly upon the stylus or needle point, and provide a contact surface of sufficient area to avoid any possible lost motion between the stylus or needle point and the mount.

If it be found that the weight of the sound box, and the pivotally supported portions of the amplifiers, horns or tone arms, is sufficiently great to have the stylus or needle point bear with too much force upon the record, means may be provided for sustaining a portion of the load of these parts. This means preferably consists of a socket p having a depressible buffer p' mounted therein. Acting to normally raise said buffer is a spring p^2 . The buffer p' is so positioned as

to engage either sections e' or i' when it is lowered to bring the stylus or needle point into engagement with the record.

The operation of the herein described phonograph is substantially as follows:—

In the following description of the operation of the herein described phonograph, it will be assumed that the double tone arm structure is used, it being understood, however, as heretofore stated that, if desired, a single tone arm may be employed without departing from the spirit and scope of the invention.

When it is desired to place a record c upon the rotatable table b , the sound box d and its appurtenances are raised together with the pivotally movable portions of each amplifier, horn or tone arm. When the sound box is so raised as indicated in dotted lines, Fig. 2, the end of the stylus or needle point may be inserted within the jaws o' and the sleeve o^2 so turned as to clamp said jaws firmly upon said stylus or needle point.

A record having been mounted upon said table, the sound box is lowered and the stylus or needle point d^2 inserted in the groove of the record.

When it is necessary to use a yielding buffer for sustaining a portion of the load of the sound box, the section e' will engage the buffer p' before the stylus or needle point engages the record and thus limit the pressure exerted by the needle upon the record.

With the rotation of the table b , the impressed sound waves upon the record vibrate the arm d' and impart a similar vibratory movement to the diaphragm d^3 . This movement of the diaphragm affecting the columns of air upon opposite sides thereof, will develop sound waves which will pass direct to the supplemental tone arms f' and g' and be transmitted therethrough to the sections $e'-i'$ of the main amplifiers, horns or tone arms.

During the rotation of the table b and the record c , carried thereby, the sound box will travel rectilinearly across the record, by reason of the arrangement of the supports upon opposite sides of said sound box.

The bar h will preserve the alinement of these supports. By supporting the sound box and the supplemental tone arm in the manner described, the stylus or needle point d^2 is maintained at substantially a constant angle with relation to the record, any fluctuation in the plane of different portions of the record being compensated for by the pivotal connections between the sections e^2-i^2 and the bells $e-i$.

By using the annulus m with the opening m' alined with the sound outlet opening g , I not only bring the column of air upon that side of the diaphragm, into accord with the column of air upon the opposite side of the diaphragm and deliver the sound waves pro-

duced between said annulus and the diaphragm to a path which will insure the discharge of substantially all of them through the sound outlet opening *g* but provide clearance for the vibratory arm *d*² without forming openings in the supplemental tone arm *g'*.

I have shown and described herein, the application of my invention to a gramophone machine wherein the sound box is propelled by and in accordance with the groove of the record. It is not my intention, however, to limit the invention to use in connection with this type of phonograph as it may be readily adapted to other types without departing from the spirit and scope of the invention.

It is not my intention to limit the invention to the precise details of construction shown in the accompanying drawings, it being apparent that such may be varied without departing from the spirit and scope of the invention.

Having described the invention what I claim as new and desire to have protected by Letters Patent is:—

1. A phonograph embodying therein a record support, a fixed bell, a tone arm pivotally mounted in relation to said bell and having a section above and projecting substantially parallel with the face of said support, a supplemental tone arm slidably and nonrotatably mounted in, axially alined with, and opening into, said tone arm section, a sound box carried by and movable with said supplemental tone arm and having the outlet opening thereof in axial alinement with said supplemental tone arm and in communication therewith, a diaphragm in said sound box, a vibratory arm operatively connected with said diaphragm and adapted to support a stylus or needle point, a pivotal bearing in axial alinement with and spaced away from said first named tone arm section, an elongated support projecting from the side of said sound box opposite to said supplemental tone arm and seated in said bearing and movable with said sound box and said supplemental tone arm, and means whereby said sound box may be moved away from said support, or toward said support to bring the stylus or needle point into engagement with the groove of the record.

2. A phonograph embodying therein a rotatable record support, a fixed bell, a tone arm pivotally mounted in relation to said bell and having a section above and projecting substantially parallel to the surface of said support, a bearing carried by said tone arm section, a supplemental tone arm slidably and nonrotatably mounted in said bearing, and axially alined with, and opening into, said tone arm section, a sound box carried by and movable with said supple-

mental tone arm and having the outlet opening thereof in axial alinement with said supplemental tone arm and in communication therewith, a diaphragm in said sound box, a vibratory arm operatively connected with said diaphragm and adapted to support a stylus or needle point, a bearing in axial alinement with and spaced away from said first named bearing, an elongated support projecting from the side of said sound box opposite to said supplemental tone arm seated in said bearing and movable with said sound box and said supplemental tone arm, a distance bar connected to said bearings respectively, whereby they will be held in alinement, and means whereby said sound box may be moved away from said support, or toward said support to bring the stylus or needle point into engagement with the groove of the record.

3. A phonograph embodying therein a rotatable record support, a fixed bell, a tone arm pivotally mounted in relation to said bell and having a section above and projecting substantially parallel with the face of said support, a supplemental tone arm slidably and nonrotatably mounted in, axially alined with, and opening into, said tone arm section, a sound box carried by and movable with said supplemental tone arm and having the outlet opening thereof in axial alinement with said supplemental tone arm and in communication therewith, a diaphragm in said sound box, a vibratory arm operatively connected with said diaphragm and adapted to support a stylus or needle point, and means whereby said sound box may be moved away from said support or toward said support to bring the stylus or needle point into engagement with the groove of the record.

4. A phonograph embodying therein a traveling record support, a fixed bell, a tone arm pivotally mounted in relation to said bell and having a section above and projecting substantially parallel with the face of said support, a bearing carried by said tone arm section, ball cups carried by said bearing, a ball mounted in each of said ball cups, a supplemental tone arm having elongated guide ways therein coöperating with said balls whereby said supplemental tone arm is slidably and nonrotatably mounted in said bearing, said supplemental tone arm being axially alined with, and opening into, said tone arm section, a sound box carried by and movable with said supplemental tone arm and having the outlet opening thereof in communication therewith, a diaphragm in said sound box, a vibratory arm operatively connected with said diaphragm and adapted to support a stylus or needle point, a pivotal bearing in axial alinement with and spaced away from said first named bearing, ball cups carried by said bearing, a ball mounted

in each of said ball cups, an elongated support carried by and movable with said sound box, said support having guide slots therein coöperating with said last named bearing

5 balls whereby said support is slidably mounted in said bearing, a distance bar connected to said bearings respectively whereby they will be held in alinement, and means whereby said sound box may be moved away from said support, or toward said support to bring the stylus or needle point into engagement with the groove of the record.

5. A phonograph embodying therein a rotatable record support, a fixed bell, a tone arm 15 comprising a movable portion consisting of parallel sections one of which is pivotally connected with said bell and the other of which is above and projects substantially parallel with the face of said support and 20 an intermediate section connecting said parallel sections, a supplemental tone arm slidably and nonrotatably mounted in, axially alined with, and opening into, said tone arm section, a sound box carried by and 25 movable with said supplemental tone arm and having the outlet opening thereof in axial alinement with said supplemental tone arm and in communication therewith, a diaphragm in said sound box and a vibratory 30 arm operatively connected with said diaphragm and adapted to support a stylus or needle point.

6. A phonograph embodying therein a rotatable record support, an amplifier having a plurality of like branches, a tone arm pivotally connected with each of said branches, said tone arms each having a section above and projecting substantially parallel with the face of said support, said sections 40 being in axial alinement one with the other, a plurality of supplemental tone arms slidably and nonrotatably mounted in, axially alined with and opening into said tone arm sections respectively, a sound box carried by 45 and movable with said supplemental tone arms and having an outlet opening upon opposite sides thereof in communication with said supplemental tone arms respectively, a diaphragm in said sound box, a 50 vibratory arm operatively connected with said diaphragm and adapted to support a stylus or needle point and means whereby said sound box may be moved away from said support, or toward said support to

bring the stylus or needle point into engagement with the groove of the record. 55

7. A phonograph embodying therein a rotatable record support, an amplifier having a plurality of like branches, a tone arm pivotally connected with each of said 60 branches, said tone arms each having a section above and projecting substantially parallel with the face of said support, said sections being in axial alinement one with the other, axially alined bearings carried 65 by said sections respectively a plurality of supplemental tone arms slidably and nonrotatably mounted in said bearings respectively, said supplemental tone arms being axially alined with and opening into said 70 tone arm sections respectively, a sound box carried by and movable with said supplemental tone arms and having an outlet opening upon opposite sides thereof in communication with said supplemental tone arms 75 respectively, a diaphragm in said sound box, a vibratory arm operatively connected with said diaphragm and adapted to support a stylus or needle point, and means whereby said sound box may be moved away from 80 said support, or toward said support, to bring the stylus or needle point into engagement with the groove of the record.

8. A phonograph embodying therein a rotatable record support, a tone arm comprising a fixed portion and a movable portion pivotally connected therewith, said last named portion having a section projecting substantially parallel with the face of said support, a supplemental tone arm slidably 90 and nonrotatably mounted in, axially alined with, and opening into, said movable tone arm portion, a sound box carried by and movable with said supplemental tone arm and having the outlet opening thereof in 95 axial alinement with said supplemental tone arm and in communication therewith, a diaphragm in said sound box, and a vibratory arm operatively connected with said diaphragm and adapted to support a stylus or 100 needle point.

In testimony whereof I have affixed my signature in presence of two witnesses.

MOSES STUART LEVUSSOVE.

Witnesses:

OTTO MUNK,
CLARICE FRANCK.
